UNITED STATES PATENT OFFICE.

THOMAS W. GRAHAM, OF DUBUQUE, IOWA.

VOTING-MACHINE.

SPECIFICATION forming part of Letters Patent No. 652,768, dated July 3, 1900.

Application filed February 14, 1899. Serial No. 705,479. (No model.)

To all whom it may concern:

Be it known that I, THOMAS W. GRAHAM, a citizen of the United States, residing at Dubuque, in the county of Dubuque and State 5 of Iowa, have invented certain new and useful Improvements in Voting-Machines; and I do hereby declare the following to be a full, clear, and exact description of the invention, such as will enable others skilled in the art to 10 which it appertains to make and use the same.

This invention relates to improvements in voting-machines, more particularly to that class of machine which registers the votes cast.

The invention comprehends generally a machine for registering the votes cast and means 15 for separately indicating the number of votes cast.

Heretofore many machines have been made and suggested for registering the votes. In 20 such machines, however, the mechanism employed has generally been of a complicated nature and more or less confusing to the average voter.

My invention is designed to overcome the 25 objections to the existing machines and may be stated generally as comprehending and including an arrangement of disks or detachable bodies so arranged that upon a vote being cast a disk or body will be deposited, a 30 mechanism for indicating the number of votes which have been so deposited, mechanism for preventing the repetition of a vote, and in mechanism for effecting the general working of the apparatus.

The invention is embodied in a construction 35 hereinafter described, and defined in the claims.

In the drawings I have shown a practical embodiment of my invention, but desire it 40 to be understood that I do not limit the improvements in their useful application to the particular construction which, for the sake of illustration, I have therein delineated.

In the drawings, Figure 1 represents a 45 front elevation of a cabinet, the same being partly broken away. Fig. 2 is a longitudinal vertical section showing parts in elevation. Fig. 3 is a rear view showing the rear of the cabinet partially removed. Fig. 4 is an enlarged detail view of a portion of the indicating plates and pointers. Fig. 5 is an enlarged detail view, partly in section, of a plunger

and its associated locking bar or pawl, parts being shown in section. Fig. 6 is a horizontal section taken through the lines 6 6 of 55 Fig. 4. Fig. 7 is a detail view of the guard.

In the drawings, A designates the walls of the cabinet of any convenient style or formation, the same being closed at its sides and provided with suitable doors or blinds A'. The front of this casing is conveniently provided with a removable case or door B, the same being in any convenient manner secured in position. This face portion extends to a point adjacent the lower end, at which 65 point there is placed a supplemental face-piece B', the upper edge of which is fashioned to fit behind the lower forward edge of the plate B, so that the removal of the supplemental plate is dependent upon the removal of the main plate. The casing is supported on a suitable base C, on which is supported a tilting platform D, the same being carried by supporting-levers D', pivoted at their forward ends on a cross-rod d. The 70 weight of the platform and long arms of the levers normally tends to elevate the short arms and allow the platform to assume a horizontal position, a further downward movement being prevented by the rear ends of the 75 levers coming in contact with the rear base-beam.

In the forward portion of the booth I form a compartment E, in which the voting, indicating, and recording mechanism and devices are located. In the front portion of the compartment is arranged a parallel series of vertical storage tubes or holders F of any convenient or desirable form in cross-section. These holders or tubes extend conveniently 80 from a point somewhat above the base to the top of the casing, at which point they are covered by the cap E'. The front faces or walls of the storage-tubes are composed of plates or strips F', screwed in or otherwise secured 85 to one of the side walls, at one edge only, their opposite edges terminating at a point adjacent the opposite wall, thereby forming between a narrow vertical opening f, which conveniently extends the length of the tubes. On the outer face of the plates F are marked 90 or stamped graduated scales f', bearing thereon a series of numbers arranged in regular order, the smaller numbers being at the top. 95 100

Within the tubes are a series of voting checks or disks, of any convenient form, their diameters being slightly less than that of the interior of the tubes, so that the disks may 5 move freely down when permitted. The number of disks in a tube correspond with the scale of numbers indicated on the face-plates, and the distance between the different scale or number marks is just equal to the thickness of a voting-disk. Resting on the tops 10 of the pile of disks in each tube is a follower F^2 , of a size to move freely down in the tube. This follower carries a pointer f^2 , extending from its lower edge through the vertical opening, its indicating end being turned at right 15 angles and extending in front of the indicating-plate. The lower edge of the pointer is straight and is arranged substantially in line with the upper face of the disk on which the 20 follower rests.

The lower ends of the rear walls of the tubes are formed with transverse grooves f^3 , and these walls rest on and are supported by the cross-beam G, fixed to the framework of 25 the casing. The tubes project laterally beyond the forward face of the beam a distance equal to about one-half the diameter of the tubes, and the face-plates of the tubes terminate at a point above the plane of the side 30 and back walls equal to the thickness of a single voting-disk. The supporting-beam, as shown in Fig. 5, projects under the rear portion of the ends of the tubes and form rests for the stack of voting-disks. The upper face 35 of the beam is grooved transversely, as at g, the grooves registering with the grooves in the back walls of the tubes for purposes presently to be stated.

Below the open end of the tubes are guide- 40 ways h, leading into a series of removable receptacles H, which are located back of the supplemental or lower face-plate B'. Into these receptacles the voting-disks are deposited, there being a receptacle for each tube. 45 The mechanism for moving the disks from the tubes may be of any convenient form or arrangement, the construction shown being operative and simple. It consists of a series of vertically-disposed levers K, which are pivot- 50 ed in brackets k, secured on a support K', extending across the casing. These levers have at their upper ends the offsets k^2 , which have suitable grasping rings or handles k^3 extending rearward beyond the inner wall of the 55 compartment E. The upper ends of these levers are located within convenient reach of the operators, while the lower ends are carried down a short distance below the end of the disk-tubes. Pivotal secured to the levers 60 at a point in line with the lower edge of the tubes are the plungers L, the same consisting conveniently of flat bars, having their forward ends reduced and fitted in the passages formed by the grooves g and f^3 . By this construction it will be seen that as one of the 65 levers is moved by drawing back its upper end its lower end, being forced in, will carry the

plunger forward, the end striking one of the disks, forcing the latter forward until it passes the beams G, and is then free to fall 70 into its collecting-receptacle, thereby registering one vote. The ends of the plungers, being reduced, are permitted a slight vertical movement, so that they will escape the lowermost disks under normal conditions, and 75 until the ends are elevated to aline with the disks no vote can be recorded. To effect the elevation of these plungers, the tilting platform is employed, which when depressed elevates suitable connecting bars or plates M. 80 These plates are loosely seated in sockets on the ends of the platform-levers and extend upward to and are pivotally connected at n to an elevating and locking bar O, which is pivoted in the sides of the casing and extends 85 entirely across the same directly below the line of plungers. The locking-bar O is located between the beam G and the lower projecting ends of the voting-levers and is pivoted eccentrically at its lower end, so that its tendency is to swing backward. Its upper end when the bar is in a vertical position is in line with the lower edge of that portion of the plungers back of the reduced ends, so that when the bar is in its vertical position it will 90 elevate all of the plungers, carrying their reduced ends into alinement with the bottom voting-disks, as plainly shown in Fig. 5. Extending rearward from the bar O is a ledge P, of a width sufficient to carry the same into 95 contact with the lower projecting ends of the voting-levers when the locking-bar is tilted back, as shown in dotted lines, Fig. 5. The movement of the bar forces the actuated lever or levers backward into their normal positions, carrying the end of the plungers out 100 from under the stack of voting-disks—in other words, resetting the machine.

It is evident that but one vote for any one candidate should be cast by one person. 110 Therefore to prevent a duplication or repetition of voting I form a groove or pocket Q in the under edge of the plungers at or near their longitudinal centers. When the plungers are in their normal position, the voter stepping on the platform raises the locking-bar, which strikes that portion of the plungers between the groove Q and reduced end. As the plungers are advanced their weight and that of the stack of disks cause the plungers 115 to move down, and as they have been forced in the locking notch or groove Q will be in a position directly above the upper end of the locking-bar which immediately enters the groove and prevents any backward movement of the operated plunger. As soon as the tilting platform is relieved of its weight 120 the locking-bar falls back, escaping from the groove and resetting the levers, as stated.

To secure a proper rapid movement of the 125 locking-bar, suitable weight-strips R may be secured to the connecting rods or plates M. In some districts women are allowed to vote for certain measures or candidates for cer-

tain offices only. In such cases it becomes necessary to lock the keys or levers other than those which are permitted to be used. To accomplish this, a pivoted plate S is secured 5 conveniently below the handles of the levers, the same extending across the machine. This plate is mounted on the pivot-rod S', suitably journaled in the sides of the casing, and which is provided at one end with an actuating-10 crank s on the outside of the booth. The free edge of the plate when swung up occupies a position directly below the handles or rings on the voting-levers. A series of removable 15 cover-plates s² are secured to the outer face of the plate S, their ends extending upward beyond the adjacent handles, thus forming a cover to conceal the handle and prevent its being grasped.

Above the ends of the voting-levers is an 20 inclined rack T, designed to secure the cards on which the names of the offices, parties, or candidates are printed. In the rear of this rack a suitable glazed window U may be placed.

25 In some instances I may secure to the upper ends of the voting-levers suitable plates V, each bearing a certain color representing particular parties or political organizations. This in many cases assists the ignorant in 30 voting—as, for instance, a political party may be designated by a red color, and if the voter desired to vote for the candidate of that party he would actuate the levers having the red plates thereon.

35 It is to be understood that a series of booths can be employed and that the number of tubes and actuating devices can be varied to suit the occasion or demand.

The lower part of the inner wall of the 40 compartment E is hinged, so that access can be had to the plunger mechanism when desired.

In operation, the mechanism being actuated as above described, the voting-disks are deposited in the various storage-receptacles, 45 and the various pointers on the followers indicate the number of disks forced from the tubes. To verify this, the deposited disks are or may be counted.

It is to be understood that the particular 50 form shown is simply one embodiment of the invention and that the nature and principle of the invention can be accomplished in various ways, and I desire it understood that my invention comprehends, broadly, the use 55 of voting-disks with suitable means for separately moving the same. I also desire it understood that I have used the term "disk" in a general sense to include any body or device which can be employed for a check or 60 counter.

Having thus described my invention, what I claim as new, and desire to secure by Letters Patent, is—

1. In a voting-machine, the combination 65 with vote-indicating instrumentalities, of a device for actuating the same and means actuating to set the device in a position to actuate

the indicating instrumentalities then locking the same after actuation, and finally resetting the same, substantially as described. 70

2. In a voting-machine the combination with vote-indicating instrumentalities, of a voting device normally out of position to actuate the instrumentalities, an actuating member for the device normally in an accessible position and means actuated by the voter for setting the device in position to actuate the said instrumentality, substantially 75 as described.

3. In a check voting-machine, the combination with a casing, of a holder for receiving and holding a series of checks, a plunger for progressively removing the checks from the holder, normally out of position to operate the checks, means actuated by the voter while 80 in the booth for adjusting the plunger to a position to operate the checks, and means for changing the relative position between the holder and plunger to cause the plunger to remove a check, substantially as described. 90

4. In a check voting-machine, the combination with a check-holder, of a plunger normally out of alignment with the checks in the holder, a platform for receiving the voter and means connected with the platform for adjusting the plunger to a position to operate the checks, substantially as described. 95

5. In a voting-machine the combination with a series of check-holders, of means for progressively removing the checks from the 100 holders, normally located out of position to remove the checks, and means actuated by the voter for adjusting said removing means to a position to operate the checks, substantially as described. 105

6. In a voting-machine, the combination with vote-indicating instrumentalities, of a voting device, normally out of position to actuate the instrumentalities, an actuating member for the device normally in an accessible position and means for setting the device for actuation and resetting the same after actuation. 110

7. In a voting-machine, the combination with a series of vertically-arranged check-holders, of a series of independent plungers for progressively removing the checks from the holders, a series of levers for moving the plungers relative to the holders, a locking-bar, means for adjusting the same and projections on the levers against which the locking-bar strikes in its return movement for resetting the levers and plungers. 115

8. In a voting-machine, the combination with a casing, of a series of vertically-disposed 125 holders therein, a series of voting-checks carried by the holders, closed storage-receptacles below the holders, a series of plungers at the lower ends of the holders for removing the checks, means for moving the plungers, a combined locking and resetting bar for the plungers and means actuated by the weight of the voter to set the bar in a locking position. 130

9. In a check voting-machine, the combina-

- tion with a series of check-holders, of a series of pivoted plungers having shoulders on their lower edges, levers for moving the plungers and a swinging bar common to all the plungers arranged to be moved into the path of the shoulders and thereby lock the plungers in actuated positions.
10. In a voting-machine, the combination of a casing, of a series of holders mounted therein, a series of disks in the holders, plungers for progressively removing the disks, a tilting platform and means actuated by moving the platform to set the plungers in a position where they can operate the disks, to lock the same against repeated movements and to reset the plungers, substantially as described.
11. In a voting-machine, the combination with a casing, of a series of vertically-disposed holders therein, a series of voting-checks carried by the holders, a series of plungers for removing the checks, means for adjusting the plungers to a position where they can operate the checks and a lever for actuating said means, substantially as described.
12. In a voting-machine, the combination with a casing, of a series of holders mounted therein, a series of voting-checks carried by the holders, a series of plungers for removing the checks, means for adjusting the plungers to a position where they can operate the checks and resetting the same, and levers for actuating said means, substantially as described.
13. In a voting-machine, the combination with a casing, of a series of vertically-disposed tubes therein, independent voting - checks within the tubes, a series of plungers at the base of the tubes, vertical levers for actuating the plungers, and a combined setting locking and resetting device for the plungers, substantially as described.
14. In a voting-machine, the combination with a series of voting-check holders, of a series of independent voting - checks carried thereby, plungers at the ends of the series of checks, means for actuating the plungers to remove the checks progressively, a swinging locking-bar common to all the plungers, a projection on the locking-bar for resetting the plungers and a tilting platform for actuating the locking-bar, substantially as described.
15. In a voting-machine, the combination with a series of voting-check holders, of independent checks carried thereby, reciprocating plungers for removing the checks progressively, a vertically-disposed lever for each plunger having a handle at its upper end, a tilting platform, means actuated by the platform for setting the plungers to a position where they can operate to remove a check and means for returning the levers and plungers to their normal position, substantially as described.
16. In a voting-machine, the combination with a series of outwardly-movable actuating handles, of a locking-plate having a series of projections spaced apart and registering with certain handles, and means for moving the plate to a position where the projections will be in front of the handles, substantially as described.
17. In a voting-machine, the combination with a series of holders, of a series of voting-checks carried thereby, a series of plungers for removing the checks, levers for actuating the plungers, a swinging plate and removable projections on the plate for covering the actuating ends of the levers, substantially as described.
18. In a voting-machine, the combination with a series of receptacles or holders for a series of voting-checks, of a series of reciprocating tilting plungers for removing the checks, means for reciprocating the plungers, a movable bar and means actuated by the voter to move the bar into contact with the plunger to tilt the same, substantially as described.
19. In a voting-machine, the combination with a series of check-holders, of a series of levers, plungers pivotally connected to the levers above the ends thereof, a swinging bar extending into the angle between the plungers and lower projecting ends of the levers, for raising the plungers and forcing the lower ends of the levers out, and means for actuating the swinging bar, substantially as described.
20. In a voting-machine, the combination with a series of holders, of a series of voting-checks carried thereby, means for removing the checks and a pivoted locking and resetting bar for adjusting and resetting said removing means, substantially as described.
21. In a voting-machine, the combination with a series of check-holders, of means for progressively removing the checks from the holders, normally in an inoperative position, means for moving the removing means to an operative position and a lever for actuating said removing means when in an operative position, substantially as described.
22. In a voting-machine, the combination of voting instrumentalities, of actuating-plungers normally out of position, for moving the same, and means actuated by the voter for adjusting said plungers to a position to operate the said instrumentalities, substantially as described.
